UNITED STATES PATENT OFFICE.

JESSE LOUIS HAWKINS, OF BAKERSFIELD, CALIFORNIA.

HEAVING PLUG FOR WELL CASINGS.

Application filed January 20, 1925. Serial No. 3,633.

To all whom it may concern:

Be it known that I, JESSE LOUIS HAWKINS, a citizen of the United States, residing at Bakersfield, in the county of Kern and State of California, have invented certain new and useful Improvements in Heaving Plugs for Well Casings, of which the following is a specification.

My invention relates to devices commonly known in the art as "heaving plugs" and which are placed at the bottom of an oil well, to seal the bottom of the casing. The purpose of the plug is to prevent the gas, present in such wells, from forcing or heaving sand or other formation into the bottom of the well and up into the casing. Instances have come under my observation where several hundred feet of sand have been heaved into a well through the failure of the heaving plug.

A heaving plug, to be successful, must not only be capable of easy adjustment to and from engagement in position, but must also be adapted for dislodgment, and removal when it becomes necessary or desirable to redrill the well or to remove the casing.

To provide a plug having these desirable features is the object of my invention, and to this end my invention consists in the novel heaving plug which I shall hereinafter fully describe, it being understood that changes in structure, form and proportion may be made within the scope of the claims hereunto appended without departing from the spirit of the invention.

Referring to the accompanying drawings—

Fig. 1 is an elevation of my heaving plug.

Fig. 2 is a vertical section of the plug on

the line 2—2 of Fig. 1, showing also in vertical section the application to the mandrel top of the plug of the combination socket of a fishing tool to be used for removing the plug when necessary.

Fig. 3 is a cross section on the line 3—3 of Fig. 1.

Fig. 4 is a partial section of the plug showing the position of the slips entering the well.

The plug is a light hollow cast-iron shell and comprises a body portion 1, the bottom of which is preferably open, as seen in Fig. 2, and a neck portion or mandrel-like top 2, with closed upper end.

In the shell wall around its circumference, say for example at equidistant points are

made the slip openings 3. Within the shell back of each opening is a wrought iron pin 4 cast into the plug body.

Pivottally mounted upon each pin is a slip 5. In practice the slip is made from a piece of round steel, and has a general segmental shape, with teeth 5' on its arcuate surface, said slip playing through the opening 3 and adapted to engage the casing 12, Fig. 2. The slip is also formed with an abutment surface at 5" which coacts with a stop 6 with which the inner wall of the shell is provided and which serves to limit the upward and inward movement of the slip, as shown in Fig. 4, when the plug is being lowered in the well casing 12 and is sufficiently retracted to enable it to pass down therein.

The slip is mounted upon its pin by means of a slot 7 at its inner end, and is held on the pin by a cotter-pin 8.

It is to be noted that the axis of movement of the slip is eccentric to its toothed surface, and is such that the center of gravity of said slip lies above the horizontal plane of its axis, whereby the projection of the slip to its engagement with the well casing is automatic.

The pins 4 upon which the slips are mounted are, with intention designed to break out under sufficient jarring stress imposed upon the plug. They are strong enough to withstand any pressure to which the plug may be subjected from below, and yet weak enough to shear off or break out of the casting and drop down inside, if the plug be jarred, and thus free the slips and enable the plug to be withdrawn from the well.

In order to thus jar the plug and to remove it, the upper or neck part 2 of the plug is made mandrel-like and is formed with a circumferential series of engaging wickers or ribs 9. This adapts it to be caught by the slips 10 of a combination slip socket 11 of a fishing tool 11', as shown in Fig. 2.

When such engagement is effected and the wire drilling rope by which the fishing tool is suspended is properly manipulated, the plug may be jarred and thereby freed as above mentioned and may then be readily removed.

I claim:

1. A heaving plug for well-casings comprising a hollow shell having openings in its side walls; casing-engaging slips function-

ing through said openings; and pivotal mountings carried by and within the shell, one for each slip, said mountings being dis-ruptable under jarring stress imposed upon 5 said shell.

2. A heaving plug for well-casings comprising a hollow shell having openings in its side walls; casing-engaging slips functioning through said openings; and pins carried by and within the shell behind and proximate to said openings, one pin for and pivotally carrying one slip, said pins being mounted and fashioned to break out under jarring stress imposed upon said shell.

3. A heaving plug for well-casings comprising a hollow shell having its lower end open and its upper end closed said upper end being formed mandrel-like to receive the socket of a fishing tool and provided 20 with means for engagement with said socket, said shell having openings in its side walls; casing-engaging slips functioning through said openings; and pins carried by and with-

in the shell behind and proximate to said openings, one pin for and pivotally carrying one slip, said pins being mounted and fashioned to break out under jarring stress imposed upon said shell through manipulation of the engaging fishing tool.

4. A heaving plug for well-casings, comprising a hollow shell having openings in its side walls and interior stops above said openings; pins carried by and within said shell proximate its openings; and casing-engaging slips eccentrically pivoted on said pins on a line below their center of gravity, adapting them for automatic play through said openings and for limiting abutment against the interior stops of the shell, said pins being fashioned and mounted to break out under jarring stress imposed upon said shell, to release the slips and permit the removal of the plug.

In testimony whereof I have signed my name to this specification.

JESSE LOUIS HAWKINS.
